UNITED STATES PATENT OFFICE.

FLORIDA SOLLEE, OF NEW YORK, N. Y.

DESIGN FOR A STOCK.

SPECIFICATION forming part of Design No. 36,896, dated April 26, 1904.

Application filed March 31, 1904. Serial No. 201,009. Term of patent 3½ years.

To all whom it may concern:

Be it known that I, FLORIDA SOLLEE, a citizen of the United States, residing in the borough of Manhattan, in the city, county, and State of New York, have invented a new, original, and ornamental Design for a Stock, of which the following is a specification, reference being had to the accompanying drawing, forming part thereof.

The figure is a perspective view of a stock, 10 showing my new design.

What I claim as new, and desire to secure by Letters Patent, is—

The ornamental design for a stock, as shown.

FLORIDA SOLLEE.
